UNITED STATES PATENT OFFICE.

FRANK J. PORWOLL, OF ST. CLOUD, MINNESOTA.

HEAT REGULATOR.

Application filed July 23, 1921. Serial No. 487,042.

To all whom it may concern:

Be it known that I, FRANK J. PORWOLL, citizen of the United States, residing at St. Cloud, in the county of Stearns and State of Minnesota, have invented certain new and useful Improvements in Heat Regulators, of which the following is a specification.

This invention relates to new and useful improvements in heat regulators and more particularly to the type employed for governing the temperature of sad-irons.

And the important object of this invention is to provide a device of the above nature whereby the iron may be maintained at any degree of temperature desirable and which will prevent the irons from overheating and thereby wasting electricity.

A further object of the invention is to provide a novel arrangement of various parts whereby the efficiency of the regulator will be increased.

Still another object of the invention is to provide a device of the above nature which consists of the minimum number of parts all of which are of a substantial construction and which may be produced at the minimum cost.

Other objects and advantages of the invention will become apparent during the course of the following description.

In the accompanying drawings forming a part of the application and wherein the numerals are employed to designate like parts throughout the several views,

Figure 1 is a longitudinal section through the sad iron with the invention applied therein,

Figure 2 is a diagrammatic view,
Figure 3 is a fragmentary top plan of the iron,

Figure 4 is an enlarged elevation of the heat adjusting mechanism,

Figure 5 is an enlarged fragmentary view of the portion thereof,

Figure 6 is an elevation of solenoid retracting mechanism,

Figure 7 is a transverse section taken on line 7-7 of Figure 6, and

Figure 8 is a horizontal transverse section taken on line 8-8 of Figure 6.

Referring now more particularly to the drawings wherein for the purpose of illustration is shown the preferred embodiment of my invention, the numeral 10 designates a sad-iron of the electric type embodying a

base 11 and a casing 12 fitted upon the base to rise therefrom in the well known manner. A handle 13 of any desired construction is secured to the top of the casing as shown in Figure 1 and electric terminals 14 extend from the rear end of the casing in the ordinary manner for association with a wire plug, not shown.

A heating element 15 of any desired construction is fastened to the upper surface of the base and conforms to the shape of the base so that the heat therefrom may be equally distributed over the base of the iron. For securing the heating element to the base, lugs 16 carried by the casing 12 overlap a piece of insulation 17 positioned upon the top of the heating element and an elongated screw 18 passes through the top of the iron casing, through the insulation, heating element and into the base. Of course this screw is suitably insulated from the heating element so as not to effect a short circuit through the iron.

In the toe of the iron the thermostat support 19 rests upon the insulation 17 and is secured thereto in any suitable manner. The lugs 16 carried by the casing of the iron project inwardly therefrom to overlap the thermostat support to prevent vertical displacement thereof. The thermostat may be of most any construction but is preferably of the type that consists generally of an elongated flexible strip having one end fastened to its support 19. The free end of the thermostat strip is provided with a non-arcing contact 21. The thermostat is adapted to be arranged directly above the heating element and approximately centrally thereof so as to be affected by any variation in the temperature of the heating element.

The heat regulating device clearly shown in Fig. 4 consists of a base member 22 secured to the insulation 17 and includes a pair of spaced standards or arms 23 each of which is provided with an opening as shown in Fig. 5. An opening in one of the arms 23 is of irregular shape as seen in Fig. 5 for reception of a correspondingly shaped portion of a sliding contact bar 24. This bar is also slidably mounted in the opening of the other arm and opposite ends of the bar extend beyond the arms 23.

A flat curved spring 25 has one end thereof secured to the base 22 of the adjustor between the arms 23 while the free end is

adapted to frictionally engage the sliding contact 24 so as to retain the latter in any desired adjusted position. The base 22 is of course provided with a binding post 26 whereby current may be passed therethrough. The sliding contact at one end is provided with an insulated upstanding arm 27 which is adapted to project up through an elongated slot 28 in the top of the iron casing 12. The uppermost end of the arm 27 is bent at right angles to provide a pointing finger 29 for cooperation with a graduated scale 30 inscribed on the top of the iron casing adjacent to the slot 28.

15 Referring now to Fig. 2, it will be seen that a solenoid 31 is positioned upon the insulating material 17 and includes a sliding core 32 the outermost end of which is slidably mounted in an upstanding bracket 33 carried by the insulation. For retaining the core retracted from the magnet or solenoid, a coil spring 34 is secured to the outermost end of the core through the eye therein and is also provided for retaining the 20 non-arcing contacts 35 carried by the core disengaged from similar contacts 36 fastened to the sheet of insulation 17.

This means for retaining the contacts 35 and 36 spaced apart may be substituted by 30 means consisting substantially of a weight 37 mounted for vertical sliding movement in a pair of upstanding arms 38 fastened to the insulation. The upper end of each arm is provided with a non-arcing contact 39 so 35 that current may pass from one contact to another when the weight 37 is elevated to the upper ends of the arms 38. One of the arms is provided with an extension 40 which projects to a point between the arms 38 and 40 the end of this extension is arranged slightly above the upper ends of the arms 38. A pair of pulleys are carried by the upper end of the extension 40 for guiding a light chain 42 which is connected at one end to the 45 weight and at its opposite end to the outer end of the core 32.

Current from any suitable source is led into the heating element 15 by means of a wire 43 and is conveyed therefrom to one of 50 the contacts 36 through the medium of a wire 44. The magnet 31 is connected to the wire 44 by wire 45 and to the binding post 26 of the adjuster by wire 46. Current from the iron is led back to the source through the 55 medium of a wire 47 having connection with the thermostat 30. The other stationary contact 36 of the magnet is connected by wire 48 to the wire 47 whereby current may be transmitted either from the stationary 60 contacts 36 to the return wire 47 or through the solenoid adjuster and thermostat to the return wire 47. If found desirable, a resistance coil 49 may be included in the system and connected at one end to the wire 43 and at its opposite end to the thermostat 20.

From the foregoing description it will be understood that the contact 21 of the thermostat and the sliding contact of the adjuster are engaged when the iron is cool so that current entering the iron may pass 70 through the heating element 15, magnet 31, into the adjuster mechanism, from where it travels through the contacts 21 and 24 into the thermostat of the iron rises to the degree to cause the flexing of the thermostatic strip, the contacts 21 and 24 are separated thereby cutting off the current and permitting the iron to cool down. As soon as the cooling action has progressed to a certain extent, the thermostatic strip will return 80 so as to engage its contact with the sliding contact 24 of the adjuster, whereupon the circuit will be established to permit current to again pass through the system.

Upon the closing of the contacts 21 and 85 24, the magnet will be energized thereby attracting the core 32 so that its contacts 35 engage the stationary contacts 36 to establish connection between the wires 44 and 48 whereby the current of the iron may advance to the return wire 47 without passing through the adjuster and thermostatic strip. However, there will be a continual vibration of the core thereby continually making and breaking of the contacts 35 thereby permitting the current to pass through the adjuster and thermostat 20.

It will be obvious that the temperature at which the current is opening and closed may be varied as desired by adjusting the sliding 100 contact 24 of the adjuster so that a greater or less amount of heat will be required to cause movement of the thermostatic strip 20.

The foregoing description and accompanying drawings have reference to what 105 might be considered to be the approved or preferred form of my invention. I desire it to be understood that I may make such changes in the construction, combination and arrangement of parts, material, dimensions, 110 etc., as may prove expedient and fall within the scope of the appended claims.

Having thus described my invention what I claim as new and desire to secure by Letters Patent is:

1. The combination with an electric heating device including a heating element, a source of electric current therefor, a pair of spaced stationary contacts one of which is electrically connected to the heating element, a solenoid having its coil electrically connected to the connection between one of said spaced stationary contacts and the heating element, the core of the solenoid being normally retracted from the coil and provided with a pair of contacts for the cooperation with the spaced stationary contacts, a thermostat contact electrically connected to the coil of the solenoid, a thermostatic strip adapted for cooperation with said last men- 120 125 130

- tioned contact, an electric wire connecting the thermostatic strip with the source of current, and a conductor connecting said wire with the unconnected contact of the spaced stationary pair of contacts.
2. The combination with an electric sad-iron including a heating element, a thermostatic strip arranged thereabove and including a contact, a contact means for cooperation with the contact of the thermostatic strip and including a pair of spaced supporting arms, a contact bar slidably mounted therein, and spring means frictionally engaging the sliding contact for retaining the same in adjusted position.
3. The combination with a heating element, a solenoid, adjustable contacts and thermostat connected in series, a pair of stationary spaced contacts one connected to the heating element and the other to the thermostat, and a pair of contacts carried by the core of the solenoid whereby the stationary contacts and those carried by the core are engaged upon energization of the solenoid.
4. The combination with a heating element, a thermostat associated therewith, an electric magnet connected in series with the thermostat and the heating element, contacts carried by the core of the electric magnet, spaced stationary contacts for cooperation with those of the core, an upright having a pulley associated therewith, and a flexible element connected to the core, and a weight connected to the other end of the flexible element for normally retracting the core from the electric magnet.
5. The combination with a sad-iron including a casing, a heating element in the iron, a thermostat arranged in the casing and connected in series to the heating element, a sliding element associated with the thermostat for regulating the amount of heat necessary for the actuation of the thermostat, the casing of the sad-iron being provided with a slot, and a handle for the sliding contact extending through the slot whereby the same can be manually controlled.
6. In a heating unit, a normally closed main circuit including a heating element, a resistance coil, a solenoid including a core having a pair of contacts, a thermostat electrically connected to said solenoid and the main circuit and including a pair of normally engaged contacts, a shunt circuit including a pair of stationary contacts adapted to be intermittently engaged by the contacts carried by the solenoid core, and means connected to the solenoid core for normally retaining the contact of the core separated from those of the shunt circuit.
7. The combination with a heating element, a thermostat associated therewith, an electric magnet connected in series with the thermostat and the heating element, contacts carried by the core of the electric magnet, stationary contacts for cooperation with those of the core, and means associated with the core for disengaging the contacts carried thereby upon deenergization of the electric magnet.

In testimony whereof I affixed my signature in presence of two witnesses.

FRANK J. PORWOLL.
